UNITED STATES PATENT OFFICE.

LOUES FRIEDMAN, OF MUNCIE, INDIANA, AND DAVID WALLACE, OF TULSA,
OKLAHOMA.

FLOWING DEVICE FOR WELLS.

Application filed June 10, 1922. Serial No. 557,262.

To all whom it may concern:

Be it known that we, LOUES FRIEDMAN and DAVID WALLACE, citizens of the United States, and residents, respectively, of Muncie, in the county of Delaware and State of Indiana, and Tulsa, in the county of Tulsa and State of Oklahoma, have invented certain new and useful Improvements in Flowing Devices for Wells, of which the following is a specification.

Our present invention relates generally to flowing devices for wells and more especially to certain improvements in our flowing device described and claimed in our Patent 1,414,402 dated May 2nd, 1922, and including among other things a downwardly opening fluid and pressure receiver which is insertable in a well casing and has an outflow line connected to its upper closed end together with a pressure tube forming the sole means of communication between the interior of the receiver and the outflow line and means within and connected to the receiver for supporting the pressure tube, whereby it is as a whole adapted to utilize the pressure within a well for the purpose of causing outflow of oil and gas in lieu of the usual pumping apparatus as well as the troublesome and expensive upkeep thereof. Through the use of such a flowing device, either the natural gas pressure within a well is taken advantage of, or gas or air pressure introduced, and it is not only true that the more or less expensive and troublesome pumping apparatus, ordinarily employed, is done away with, but an important and decided advantage is obtained by virtue of the steady uniform outflow as distinguished from the intermittent outflow of a pumping apparatus, making the external separation of liquid and gas a much easier operation and one that can be carried out much more effectively.

According to our present improvements we utilize an outflow tube or tubes opening into the outflow line in addition to the pressure tubes, one at least of which outflow tubes opens into the receiver, and another of which may be extended to any suitable point below the receiver in order to take care of water collecting in the lower part of the well. The flow of fluid through these tubes is induced by suction in the outflow line by virtue of the jets of oil and gas from the upper outlet ends of the pressure

tubes and the result is a more steady augmented outflow of oil and gas than would otherwise take place.

We also provide certain improvements and refinements utilized in case of the introduction of air or gas pressure where there is insufficient pressure in a well, so that all danger of back pressure within a well which might otherwise retard the free inflow of oil, is avoided.

With these and certain other objects, the advantages of which will be apparent, our invention resides in the improved apparatus shown in the accompanying drawing which forms a part of this specification and illustrates our invention, and in which,

Figure 1 is a vertical sectional view through our improved apparatus with the lower end of the receiver open,

Figure 2 is a similar view taken through a slightly modified form and at right angles to Figure 1, for instance on line 2-2 of Figure 4, showing the lower end of the receiver plugged and illustrating the use of pressure supply means,

Figure 3 is a detail perspective view of the plug through which the several outflow and pressure tubes are extended, and

Figure 4 is a horizontal section taken on line 4-4 of Figure 2.

Referring now to these figures, and as in our previous patent, our improved apparatus is connected to the lower end of an outflow line in the form of a pipe 10, to which the upper end of the cylindrical barrel 11 is connected as by means of a coupling 12. This barrel 11 is externally threaded at its upper portion to receive thereon an internally and externally threaded supporting ring 13, above which ring and between the same and the coupling 12 an expansion gasket 14 is provided between washers 15 and 16. This gasket is adapted to closely interfit the well casing 17 and to seal or substantially seal the latter at whatever point it is stationed within the well casing in order to confine and trap gas pressure in a well below the gasket.

Connected to the cast ring 13 by virtue of its external threads is the internally threaded portion 18 at the upper end of the receiver 19 in the form of a cylindrical shell which surrounds the lower portion of the barrel 11 in spaced relation so as to form a chamber between these parts upwardly into

which oil and gas are free to flow with the lower end of the receiver or shell open as it is shown in Figure 1 when there is sufficient pressure in the well to bring about the 5 outflow of oil and gas without the introduction of pressure from the outside, and it is to be understood that by the use of a plug 20 within the upper portion of the barrel 11 and pressure tubes 21 whose upper ends are 10 extended through this plug and thus open into the outflow line or pipe 10 and whose lower angular ends are extended laterally through the lower portion of the barrel 11 as at 22, the device as a whole will operate 15 with a very small pressure within an oil well so as to produce a continuous effective outflow in a greater majority of wells.

In some few instances however it is necessary to introduce gas or air pressure through 20 a pressure supply pipe 23 leading downwardly into the casing alongside the outflow pipe or line 10 and extending downwardly through the gasket 14 and supporting ring 13 with its lower end opening into 25 the receiver or shell 19 as clearly seen in Figure 2. With the lower end of the receiver or shell 19 entirely open as in Figure 1, pressure from this supply pipe 23 would find its way into the lower portion of the 30 well and unless great care was exercised to bring about supply of just the proper amount of pressure at all times, there would be considerable danger of oversupply and of back pressure in the well which would 35 prevent free inflow of oil. It is for this purpose that we propose in such instances to close the lower end of the shell or receiver 19 as by means of a plug 24 seen in Figure 2 secured in any suitable manner 40 within the lower end of the shell or receiver and downwardly through which the lower end of the barrel 11 opens. In this way the pressure from pressure supply pipe 23 finds its way into the pressure tubes 21 and upwardly 45 through these tubes into the outflow line 10 but cannot affect the oil sands in the manner just above described. As the pressure passes into the outflow line 10 it produces a suction which draws oil upwardly 50 through outflow tubes 25 and 26 mounted through the plug 20 as most plainly seen in Figure 3 and whose upper ends open into the outflow pipe or line 10 immediately above the plug. The lower end of at least 55 one of these outflow tubes, the outflow tube 25 as shown, opens into the barrel 11 whose lower end is of course open to the inflow of oil, extending as it does below the lower closing plug 24 of the receiver. The other 60 tube 26 may be extended downwardly below the lower end of the barrel 11 as seen in Figure 1 so as to open into and receive water collecting below the oil and, where the head of oil requires, the lower threaded end of 65 the barrel 11 may be connected by a cou-

pling 27 to a perforate extension tube 28 providing for the inflow of oil through the perforations 29, in turn connected by a coupling 30 to an imperforate extension tube 31 as seen in Figure 2. In this form the outflow tube 26 is extended downwardly through the perforate extension tube 28 and into the imperforate extension tube 31 and may be either connected to a receiving bell and the like 32 adapted to close the lower portion of the extension tube 31 to receive the water, or where the tube 26 is either without the receiving bell 32 or the latter does not close the extension tube 31, a plug 33 may be employed within the extension tube to close the same around the outflow tube 26 above the lower receiving end of the latter.

It is understood of course that for operating purposes in the usual well where the introduction of gas or air pressure is unnecessary, the lower end of the receiver or shell 19 remains open, plug 24 being omitted, and pressure from the well itself finds its way upwardly into the pressure tubes 21 and also into and through the outflow tubes 25 and 26, all of which tubes open at their upper ends into the outflow line or pipe 10.

We claim:

1. A flowing device for oil wells including an outer shell closed at its upper end, an outflow pipe extending from the said upper end of the shell, a barrel connected to and depending within the shell having its upper portion closed, one or more pressure tubes within the barrel having their upper ends opening through the upper closed portion of the barrel and into the outflow pipe, and having their lower ends opening through the wall of the barrel and into the shell, and one or more outflow tubes in the barrel having their upper ends opening through the upper closed portion of the barrel and into the outflow pipe.

2. A flowing device for oil wells including an outer shell closed at its upper end and having an outflow line connected to said upper end by means of which the shell may be lowered into a well casing, a barrel connected to and depending within the shell, and outflow tubes having their upper ends opening into the outflow pipe, certain of which tubes open downwardly into the barrel and certain of which tubes open at their lower ends through the barrel and into the shell.

3. A flowing device for oil wells including an outer shell closed at its upper end and having an outflow line connected to said upper end by means of which the shell may be lowered into a well casing, a barrel connected to and depending within the shell, and outflow tubes having their upper ends opening into the outflow pipe, certain of which tubes open downwardly into the barrel and certain of which tubes open at their lower ends through the barrel and into the shell.

lower ends through the barrel and into the shell, means closing the lower end of the shell around the barrel, and a pressure supply pipe having its outlet end opening into the shell for the purpose described.

4. A flowing device for oil wells including an outer shell closed at its upper end and having an outflow line connected to said upper end by means of which the shell may be lowered into a well casing, a barrel connected to and depending within the shell, and outflow tubes having their upper ends opening into the outflow pipe, certain of which tubes open downwardly into the barrel and certain of which tubes open at their lower ends through the barrel and into the shell, and an extension tube connected to and depending from the lower end of the barrel and within which another of said outflow tubes is extended.

5. A flowing device for oil wells including

an outer shell closed at its upper end and having an outflow line connected to said upper end by means of which the shell may be lowered into a well casing, a barrel connected to and depending within the shell, and outflow tubes having their upper ends opening into the outflow pipe, certain of which tubes open downwardly into the barrel and certain of which tubes open at their lower ends through the barrel and into the shell, and an extension tube connected to and depending from the lower end of the barrel and within which another of said outflow tubes is extended, said extension tube having a perforate section above the lower end of the last mentioned outflow tube, and means closing the said extension tube adjacent to the lower intake end of the last mentioned pressure tube.

LOUES FREIDMAN.
DAVID WALLACE.
